VULCANIZING SEAL

Henry E. Thompson, Dobbs Ferry, N. Y., assignor
to Anaconda Wire & Cable Company, a corpora-
tion of Delaware

Application June 17, 1946, Serial No. 677,347

2 Claims. (Cl. 286—16)

1

This invention relates to continuous vulcanization of rubber-covered wire and, more particularly, to a seal adapted to provide substantially pressure-tight closure of the end of a continuous vulcanizing chamber through which a rubber-covered wire is moved. The vulcanizing seal of the invention provides such closure of a vulcanizing chamber while permitting substantially non-distortionary movement of the covered wire through the seal.

In the production of rubber-covered wire, the wire is passed through an extrusion die wherein a covering of plastic rubber is applied about the wire. In order to vulcanize this rubber covering, the wire leaving the extrusion die is passed through an elongated vulcanizing chamber containing a vulcanizing medium (steam) under super-atmospheric pressure. The maintenance of high pressure steam within the vulcanizing chamber requires the use of pressure seals at each end of the vulcanizing chamber. Not only must these seals be capable of maintaining a steam pressure of, say two hundred pounds per square inch in the vulcanizing chamber, but they must be such as to avoid deleterious distortion or other damage to the rubber covering about the wire. Numerous seals have been proposed and used heretofore for this purpose, but seals which have been capable of maintaining the desired steam pressure within the vulcanizing chamber without excessive loss of steam have tended to damage the rubber covering on the wire, and those seals which have not damaged the covering have not generally been capable of maintaining the desired steam pressure without considerable loss of steam through the seals. Furthermore, these and other seals proposed and used heretofore require considerable maintenance and frequent replacement of parts.

The present invention contemplates a novel seal adapted to be used at either or both ends of a continuous vulcanizing chamber for the treatment of rubber-covered wire. The novel seal of this invention provides a closure of the desired characteristics without requiring the use of any extraneous medium or agent under high pressure to counteract the tendency of the high pressure vulcanizing medium to escape.

The vulcanizing chamber seal of the present invention comprises a plurality of steam condensing chambers serially arranged within the end of the vulcanizing chamber. The condensing chambers are separated from one another by a partition provided with an orifice of sufficient size to permit substantially non-distortionary movement of the wire therethrough. The orifice in

each partition is also sufficiently small to prevent unhindered escape of the vulcanizing medium therethrough. Cooling means are provided to effect heat-transfer cooling of steam in each of the condensing chambers. In a particularly advantageous embodiment of the invention, the cooling means comprises a water jacket surrounding the end of the vulcanizing chamber provided with the steam condensing chambers. The cross-sectional area of the clearance space between the wire and the orifice in each partition is preferably less than about ten percent of the internal cross-sectional area of the steam condensing chambers. This arrangement provides a series of zones between the spaced partitions within the end of the vulcanizing chamber containing the steam under successively decreasing pressures, thus minimizing the escape of steam through the orifices which are nevertheless of sufficient size to permit relatively free movement of the rubber-covered wire therethrough. Thus, the invention contemplates a method of sealing the end of a continuous vulcanizing chamber of the type described hereinbefore by establishing adjacent the end of the steam vulcanizing chamber and about the wire moving therethrough a series of zones of the vulcanizing steam under successively decreasing pressures, these zones being cooled by means of heat transfer without the need of passing a cooling medium in direct contact with the steam.

These and other novel features of the invention will be further understood from the following description taken in conjunction with the accompanying drawing, in which the single figure shows the novel seal of the invention applied at both ends of a continuous vulcanizing chamber.

The wire 5 to be covered with rubber is passed through an extrusion die 6 to which rubber under pressure is supplied through a delivery line 7. The wire leaving the extrusion die 6 is thus covered with plastic rubber which must be vulcanized before it is of practical use.

The rubber-covered wire leaving the extrusion die 6 passes through an entry seal 8 of an elongated tubular chamber 10 filled with high pressure steam, adapted to effect vulcanizing of the rubber covering during passage of the wire throughout the length of the chamber. The entry seal 8 may be directly connected to the extrusion die chamber as shown in the drawing, or it may be physically separated therefrom in order to permit visual inspection of the rubber-covered wire as the wire leaves the die. The vulcanizing steam, under super-atmospheric pressure of, say, about

two hundred pounds per square inch, is supplied through a pressure line 11 communicating with the vulcanizing chamber 10. The vulcanized wire is withdrawn from the vulcanizing chamber through an exit seal 12 at the discharge end of the vulcanizing chamber.

The vulcanizing chamber, as shown in the drawing, is provided with a seal in accordance with the invention at both ends. However, my novel seal may be used at only the discharge end of the vulcanizing chamber, relying upon some other conventional seal at the entrance to the vulcanizing chamber where the difficulty of sealing is lessened by the sealing effect of the extrusion die 6.

The vulcanizing chamber seal, in accordance with the invention, may be provided within and about the end portion of the vulcanizing chamber itself or it may embody a separate chamber portion which is secured to the vulcanizing chamber. Thus, the "end portion" of the vulcanizing chamber referred to herein and in the claims is intended to include the actual end portion of the vulcanizing chamber as well as a separate end portion secured thereto. The end portion 13 of the vulcanizing chamber is provided in accordance with the invention with a plurality of partitions 14 serially positioned in spaced relationship therewithin. The partitions may be formed integrally with the rest of the chamber 13 or may comprise plugs or the like inserted within the chamber and appropriately secured in proper position. The plurality of spaced partitions 14 separate the end portion of the vulcanizing chamber into a plurality of zones or steam condensing chambers between which communication is provided only by means of longitudinal orifices 15 provided through each partition. The orifices 15 are of sufficient size to permit substantially non-distortional movement of the wire therethrough. That is, the orifices 15 are of such size that the rubber-covered wire may pass therethrough without sufficient frictional contact or abrasion to damage or in any way adversely affect the quality of continuity of the rubber covering. However, the size of the orifices is made sufficiently small to prevent unhindered escape of the steam between the interior surface of the orifice and the surface of the covered wire passing through the orifice. Thus, each of the orifices 15 is of sufficient size to act somewhat as a reducing valve, the space between the surface of the covered wire and the interior of each orifice providing a restricted opening through which steam, and water resulting from condensation of the steam, may pass into the open zone or space between adjacent partitions. I have found it particularly advantageous to maintain the cross-sectional area of the free space between the wire and the interior surface of the orifice less than about ten percent of the internal cross-sectional area of the free space zone between adjacent partitions. In this manner, the high pressure steam within the vulcanizing chamber 10 escapes through the small space between the wire and the orifice of that partition which is positioned immediately adjacent the end of the vulcanizing zone of the chamber 10. This restricted escape of high pressure steam results in the establishment of a zone of somewhat reduced pressure steam between this partition and the second (next) partition. Escape of this reduced-pressure steam through the orifice 15 in the second partition further reduces the steam pressure within the second

free space zone between the second and third partition. Thus, a decreasing pressure gradient is established in the successive zones extending from the high pressure vulcanizing zone within the chamber 10 toward the extreme end of the chamber. The decreasing pressure serves to cool the steam so that, in effect, the zones or spaces between partitions 14 comprise steam condensing chambers.

The extent of pressure reduction from one zone or condensing chamber to the next in the seal is enhanced in accordance with the invention by a cooling jacket 16 surrounding that end portion of the vulcanizing chamber which is provided internally with the steam condensing chambers. Any suitable cooling medium such as water may be used, the cooling medium being circulated through appropriate delivery and discharge openings. The cooling effect provided by the cooling jacket augments the cooling effect provided by expansion of relatively high pressure steam through the restricted space partition orifice into the relatively large free space between each partition and the next adjacent partition. As a result, the steam is largely condensed to water before it reaches the end of the seal so that in at least one or more of the last partitions in the seal the free space between the wire and the interior surface of the orifice 15 may be filled with water comprising the condensed steam. The thickness of the partition (that is, the length of the longitudinal orifice 15 in the partition) thus serves to increase the resistance to flow of water through the restricted space between the wire and the interior surface of the orifice 15 so as to enhance the pressure drop between adjacent zones on opposite sides of each partition without requiring firm physical contact between the covering of the wire and the interior of the orifice. The relatively high velocity of this water (condensed steam) flowing through the small free space in the orifice 15 in one partition and discharging into the relatively large volume of the space zone between this partition and the next adjacent partition creates a substantial pressure drop in accordance with Bernoulli's theorem. The combined effects of the spacing between the plurality of partitions, the thickness of the partitions, and the free but limited space between the surface of the covered wire and the interior surface of each partition orifice 15, coupled with the cooling effect of the cooling jacket 16, result in a seal which is capable of preventing the escape of an appreciable amount of vulcanizing steam from the vulcanizing chamber without deleteriously affecting the quality or shape of the covering about the wire.

In order to remove condensed steam from the discharge end of the seal, a discharge line 17 is provided which communicates advantageously with the extreme end portion of the chamber beyond the cooling jacket 16. The end of the exit portion of the seal may be provided with advantage with an additional partition 14 similar to the others used in the seal and held in place by a collar 18 threaded over this exit end of the seal chamber.

Seals, in accordance with the invention, provided at both ends of the vulcanizing chamber may be provided with the same number of steam condensing chambers or a different number of such chambers. In general, a larger number of condensing chambers is required in the exit seal than is required in an entry seal attached to the extrusion die 6 due to the assisting sealing effect

of the extrusion die adjacent the entry end of the chamber. The number of steam condensing chambers used in seals in accordance with my invention will depend upon the amount of steam pressure maintained within the vulcanizing chamber and the amount of free space or tolerance between the surface of the rubber-covered wire and the interior surface of the partition orifices 15. By way of illustration, and not as any limitation to the invention, I have found that with a vulcanizing steam pressure of two hundred pounds per square inch and with the cross-sectional area of free space between the surface of the covered wire and the interior of the partition orifices 15 limited to not more than ten percent of the internal cross-sectional area of the steam condensing chambers, effective sealing may be provided at the exit end of the vulcanizing chamber with four or five condensing chambers within the cooling-jacketed end portion of the vulcanizing chamber.

I claim:

1. A seal for the end of a continuous vulcanizing chamber through which a rubber-covered wire is passed continuously in contact with a vulcanizing atmosphere of high pressure steam maintained within the chamber, said seal comprising a plurality of steam condensing chambers serially arranged within the end of the vulcanizing chamber, a cooling jacket surrounding said steam condensing chambers, each of the chambers being separated from its adjoining chamber by a partition provided with an orifice of sufficient size to permit movement of the wire therethrough free from distortion of its rubber covering, said partitions being of such thickness that said orifice has the form of an elongated tube which, when occupied by said wire, provides an elongated annulus about the wire having a cross-sectional area less than about ten percent of the internal cross-sectional area of said steam condensing chambers, whereby said annulus in each partition constitutes a reducing valve adapted to materially reduce the pressure of the steam in each of the successive chambers in a direction proceeding from the vulcanizing chamber to the end of the seal and said annulus further contributes by its considerable length relative to its cross-sectional area to pressure reduction between adjoining steam condensing chambers by

the frictional resistance to the flow of steam and condensed steam therethrough.

2. A seal for the end of a continuous vulcanizing chamber through which a rubber-covered wire is passed continuously in contact with a vulcanizing atmosphere of high pressure steam maintained within the chamber, said seal comprising a plurality of steam condensing chambers serially arranged within the end of the vulcanizing chamber, a cooling jacket surrounding said steam condensing chambers, each of the chambers being separated from its adjoining chamber by a partition provided with an orifice of sufficient size to permit movement of the wire therethrough free from distortion of its rubber covering, said partitions being of such thickness that said orifice has the form of an elongated tube which, when occupied by said wire, provides an elongated annulus about the wire constituting the sole means for the removal of steam and condensate from each chamber to the last chamber of the series, said annulus having a cross-sectional area less than about ten percent of the internal cross-sectional area of said steam condensing chambers, whereby said annulus in each partition constitutes a reducing valve adapted to materially reduce the pressure of the steam in each of the successive chambers in a direction proceeding from the vulcanizing chamber to the end of the seal and said annulus further contributes by its considerable length relative to its cross-sectional area to pressure reduction between adjoining steam condensing chambers by the frictional resistance to the flow of steam and condensed steam therethrough, and a drain for removing condensate from the last chamber of the series.
